UNITED STATES PATENT OFFICE.

WILLIAM ALBERT WHALEN, OF BALTIMORE, MARYLAND, ASSIGNOR TO
THE AUGUST MAAG COMPANY, OF SAME PLACE.

DESIGN FOR A CAKE-PAN.

SPECIFICATION forming part of Design No. 33,705, dated December 11, 1900.

Application filed November 6, 1900. Serial No. 35,681. Term of patent 3½ years.

To all whom it may concern:

Be it known that I, WILLIAM ALBERT WHALEN, of Baltimore, State of Maryland, have invented and produced a new and original Design for a Cake-Pan, of which the following is a full, clear, and exact description, reference being had to the accompanying drawings, forming a part thereof.

In the accompanying drawings, Figure 1 is a perspective view, and Figs. 2 and 3 are views in section, of the cake-pan.

The leading feature of my design consists of a cake-pan comprising an angular base, an outwardly and upwardly projecting wall having V-shaped corrugations forming a star-shaped periphery, and triangular vertical portions between the outwardly-flaring corrugations.

1 represents a hexagonal base having an outwardly and upwardly projecting side wall 2, having V-shaped corrugations and the periphery thereof forming a six-pointed star, the bend 3 in the wall 2, forming the extreme points of the star, merging into the angles of the hexagonal base, while the bends forming the juncture of the points of the star terminate in upright triangular portions 4, the base of which merges into the sides of the hexagonal base 1.

What I claim is—

The design for a cake-pan herein shown and described.

WILLIAM ALBERT WHALEN.
